Primary Examiner — Lucy Lieberman(74) *Attorney, Agent, or Firm* — Withrow & Terranova, PLLC(57) **CLAIM**

The ornamental design for slotted side support, as shown and described.

DESCRIPTION

FIG. 1 is a top perspective view of a first embodiment of a slotted side support showing my new design, which may be used as a side support in bedding or cushions as an example; FIG. 2 is a top view of the slotted side support of FIG. 1; FIG. 3 is a bottom view of the slotted side support of FIG. 1; FIG. 4 is a front view of the slotted side support of FIG. 1; FIG. 5 is side view of the slotted side support of FIG. 1; FIG. 6 is a top perspective view of a second embodiment of the slotted side support, which may be used as side support in bedding or cushions as an example; FIG. 7 is a top view of the slotted side support of FIG. 6; FIG. 8 is a bottom view of the slotted side support of FIG. 6; FIG. 9 is a front view of the slotted side support of FIG. 6; and, FIG. 10 is side view of the slotted side support of FIG. 6. Both embodiments of the slotted side support are shown with a symbolic break. The appearance of any portion of the article between the break lines forms no part of the claimed design.
